EDWARD MASTERS, OF CLEVELAND, OHIO.

Letters Patent No. 68,522, dated September 3, 1867.

IMPROVED YARD FOR SHIPS.

The Schedule referred to in these Letters Patent and making part of the same.

TO ALL WHOM IT MAY CONCERN:

Be it known that I, EDWARD MASTERS, of Cleveland, in the county of Cuyahoga, and State of Ohio, have invented a new and improved Yard for Ships; and I do hereby declare, that the following is a full, clear, and exact description thereof, which will enable those skilled in the art to make and use the same, reference being had to the accompanying drawings, forming part of this specification, in which—

Figure 1 is a side view of my improved yard, part of the central part being broken away to show the construction.

Figure 2 is a detail cross-section of the same taken through the line $x x$, fig. 1.

Similar letters of reference indicate corresponding parts.

My invention has for its object to furnish an improved yard for ships, stronger, lighter, more durable, and more easily repaired than those constructed in the ordinary manner, and it consists in an improved yard, made in three parts, and strengthened by stay-brace and ring-plates.

A is the central part or hub of the yard, which may be made hollow, or with a longitudinal hole through its centre, for the reception of the ends of the yard-arms B, which meet in the centre of the said hub A. C are flanged sockets, fitting upon the outer ends of the yard-arms B; and through the flanges or ring-plates c', formed upon or attached to them, are formed holes for the passage of the brace-rods D, the other ends of which pass along longitudinal grooves in the central piece or hub A, so as to be flush with the surface of said hub. The brace-rods D are secured and strained by nuts screwed upon their ends, or, if desired, heads may be formed upon one end of the said rods, and the nuts screwed upon their other ends. The central part or hub A is strengthened and the brace-rods are confined to their place by bands E, passing around the ends of said hub, as shown in fig. 1. The bands E are kept from working off the ends of the hub A by the ring-plates F, through which the brace-rods D pass, and by which the said plates are held pressed up against the ends of the part A. G are ring-plates, one or more of which are placed upon and secured to each of the arms B of the yard, to receive the brace-rods D, and thus strengthen the yard. The yard is sustained, connected to the rigging, and operated in the ordinary manner.

This construction of the yard also enables the sailors to work upon it in reefing and furling the sails, &c., with more ease and safety, thus enabling them to do their work quicker and better. It also enables any part of the yard that may be broken or injured to be replaced without lowering the entire yard.

I claim as new, and desire to secure by Letters Patent—

An improved yard, made in three parts, A B B, and strengthened by brace-rods D and ring-plates c' G F, substantially as herein shown and described and for the purpose set forth.

EDWARD MASTERS.
